FIG. 5.

Burton P. Hall Inventor

By his Attorney

Israel Benjamins.

UNITED STATES PATENT OFFICE.

BURTON P. HALL, OF FANWOOD, NEW JERSEY.

SECTIONAL SHIPPING-CASE.

1,261,123.

Specification of Letters Patent. Patented Apr. 2, 1918.

Application filed August 23, 1917. Serial No. 187,905.

To all whom it may concern:

Be it known that I, BURTON P. HALL, a citizen of the United States, residing at Fanwood, in the county of Union and State 5 of New Jersey, have invented a new and useful Sectional Shipping-Case, of which the following is a specification.

My invention relates to improvements in shipping cases made in sections, and it 10 consists in the novel features hereinafter more fully described.

The objects of my improvement are:

First: To provide a shipping case, which may be readily assembled from its elements, 15 and which may just as readily be taken apart and returned to the sender, if need be, in small bulk.

Second: To produce a shipping case, consisting of detachable elements, which may 20 be assembled into sections of any size or into any number of sections.

Third: To have said sectional shipping case simple, durable and inexpensive.

I attain these objects by the article illustrated in the accompanying drawings or by any mechanical equivalent or obvious modification of the same.

In the drawings Figure 1 is an elevation of my shipping case consisting of a single 30 section, with the side plates omitted for the sake of clearness.

Fig. 2 is an end view or projection of said case shown with the side plates, and omitting the fastenings of the same.

Fig. 3 is a top view or plan of said case, 35 omitting the side plates.

Fig. 4 is a view of my shipping case consisting of more than one section, showing one of the side plates of the case, and 40 omitting the other side plate.

Fig. 5 is an end view of the shipping case shown in Fig. 4.

Similar numerals and letters refer to similar parts throughout the several views.

11, 11 designate the base boards of the sections of my shipping case, which base boards are shown in Figs. 1, 3 and 5 as having each the transverse grooves or mortises 11^a near each end and on the upper and 45 lower sides thereof. Said base boards 11, 11 are also shown in Figs. 1, 2 and 3 as having the sockets 11^b for securing thereto any articles which are to be packed for shipment, such as the bulb 14 and the sprinkler head 15.

The base boards 11 are shown in Figs. 1

and 4 as connected by the vertical struts 12, which have their upper and lower ends fitting into the corresponding transverse grooves 11^a of said base boards 11.

The rectangular structure shown in Fig. 1 is completed into a case by fastening the vertical covers or side plates 13 and 13^a to said base boards 11 and struts 12 on both sides thereof, as shown in Fig. 2.

Either wood screws or any other suitable fastenings may be employed.

Where more than one section of the case is to be used broadwise, as shown in Fig. 5, the cross ties 16 are employed to bind 70 the adjacent sections together by means of the tongue on one side of each of said ties fitting into the corresponding transverse grooves 11^a of the base boards 11 on the outside of said sections of the case. To augment the number of sections vertically, 75 additional base boards 11 and vertical struts 12 are added as shown in Fig. 4.

The case disclosed by both Figs. 4 and 5 consists of four sections. The number of 80 sections may be larger or smaller, however, if desired.

The side plates 13^b and 13^c, shown in Fig. 5, are only larger in size, but otherwise they don't differ from the side plates 13 and 13^a. 85 The grooves 11^a are shown as rectangular in cross-section; this serves to facilitate the assembling and collapsing of my shipping case.

Instead of employing tapped sockets 11^b 90 for securing thereto the articles to be shipped, any other suitable means of attachment may be employed; some articles may even be packed loose, if desired.

The size and shape of all the elements of 95 my sectional shipping case may be altered, if desired. I prefer not to employ any fastenings for connecting said struts 12 and ties 16 to said base boards 11, so as to be able readily to assemble the case and to take 100 it apart again; the side plates only being secured to the other elements of my case; but, if desired, fastenings may also be employed for some or all of said elements, thereby realizing part of the advantages of 105 the design of my shipping case.

Many other changes could be made in my shipping case within the scope of my invention.

I do not, therefore, restrict myself to the 110 details of my shipping case, but I intend to include also all mechanical equivalents and

reasonably obvious modifications of the same within the scope of my invention.

What I claim as my invention and desire to secure by Letters Patent is:

- 5 1. A collapsible shipping case comprising sets of elements normally disunited and adapted to be assembled into adjacent sections, each set of said elements comprising base boards having transverse grooves near 10 their ends on opposite sides thereof, struts adapted to fit at their ends into the grooves on the sides of said base boards corresponding to the inside of the assembled case, cross ties having tongues adapted to fit the grooves 15 on the sides of said base boards corresponding to the outside of the assembled case, said ties being adapted to extend across the adjacent sections of the assembled case from side to side thereof, and side plates adapted 20 to be fastened to said boards, struts and ties, and thereby to keep said assembled sections from collapsing.

2. A collapsible shipping case comprising

sets of elements normally disunited and adapted to be assembled into adjacent tiers 25 of sections, each set of said elements comprising three or more base boards adapted to be placed in parallel positions one above the other, said base boards having transverse grooves near their ends on opposite sides 30 thereof, struts adapted to fit at their ends into the grooves on the sides of said base boards corresponding to the inside of the assembled case, said struts being adapted to be placed between the successive base boards, 35 cross-ties having tongues adapted to fit the grooves on the sides of said base boards corresponding to the outside of the assembled case, said ties being adapted to extend across the adjacent tiers of sections of the assembled case from side to side thereof, and side plates 40 adapted to be fastened to said boards, struts and ties and thereby to keep said assembled tiers of sections from collapsing.

BURTON P. HALL.
